WALLACE W. WILLIAMSON, OF SYRACUSE, NEW YORK.

DENTAL ENGINE.

No. 863,478.

Specification of Letters Patent.

Patented Aug. 13, 1907.

Application filed January 7, 1907. Serial No. 351,135.

To all whom it may concern:

Be it known that I, WALLACE W. WILLIAMSON, a citizen of the United States, and a resident of Syracuse, in the county of Onondaga, in the State of New York, 5 have invented new and useful Improvements in Dental Engines, of which the following, taken in connection with the accompanying drawings, is a full, clear, and exact description.

This invention relates to the class of dental-engines 10 comprising an electric-motor and mechanism driven thereby for transmitting the power to the various kinds of instruments used by dentists.

The chief object of the present invention is to produce a dental-engine of that character wherein the 15 power-transmitting mechanism shall permit of regulation so as to cause the instrument to be driven at different speeds as may be desired, and to provide simple and convenient manually-operated means for either changing the speed of the transmission mechanism or 20 throwing the said mechanism into and out of operative relation with the motor, and furthermore to provide the motor-supply circuit with simple and reliable circuit-making and breaking devices controlled by the manually-operated means whereby the circuit will be 25 closed when the transmission-mechanism is thrown into operative condition, and opened when the said mechanism is thrown out of operative condition.

Another object of the invention is to produce a dental-engine which shall permit the motor and power- 30 transmitting mechanism to be located quite remote from the manually-operated device for controlling the said mechanism and aforesaid circuit-making and breaking means, said manually-operated devices being designed to be placed in a convenient position upon the 35 floor adjacent to the dental-instrument.

To that end the invention consists in the novel construction and arrangement of the component parts of the power-transmission mechanism and electric-circuit-making and breaking devices, in combination with 40 a motor, and the novel arrangement of the foot-operated means for controlling said mechanism and circuit-making and breaking devices as hereinafter fully described and set forth in the claims.

In the accompanying drawings, Figure 1 is a front 45 view of the dental-engine embodying my invention; Fig. 2 is a side view of the same; Fig. 3 is a plan view; Fig. 4 is an enlarged vertical section taken on the line —X—X— in Fig. 1; Fig. 5 is an enlarged detail view of the electric-circuit-making and breaking switch and 50 means for actuating the same; Fig. 6 is a sectional view of said switch taken on the line —Y—Y— in Fig. 5 and showing more clearly the electric connections and insulated contacts; Fig. 7 is a detail face view of the stationary contact adapted to be engaged by the contact 55 of the switch; Fig. 8 is an enlarged section of the foot-operated device for controlling the power-transmission

mechanism and circuit-making and breaking switch and taken on the line —Z—Z— in Fig. 2; Fig. 9 is a detail inverted plan view of the disk; and Fig. 10 is a detail plan view of the plate which is designed to be secured to a floor and to which the aforesaid disk is pivotally connected.

Similar numerals of reference indicate corresponding parts:

—1—represents an electric-motor having the usual inclosing-case and —2—2X—denote the wires of a suitable supply-circuit. The motor-case is provided with a plate —3— for fastening the same to a wall or other suitable support indicated at —4— in Figs. 2 and 3 of the drawings.

The shaft —5— of the motor is preferably disposed upright and has its upper end protruding from the inclosing-case, and to said end is rigidly fastened a horizontal disk —6— arranged concentric to the shaft and formed with a central depression —7— in its upper face 70 as clearly shown in Fig. 4 of the drawings.

Upon the motor-case is suitably mounted a bracket comprising two upwardly extending arms —8—8X— provided with coinciding bearings —9—9— disposed in horizontal alinement, in which bearings is supported an irrevolvable longitudinally-shiftable shaft —10— extending diametrically over the disk —6—. On said shaft is journaled a wheel —11— which is held from moving endwise of the shaft by means of collars —12—12— secured to the said shaft. Said wheel is 85 adapted to be frictionally driven by the disk —6— and is formed with a groove —13— in which runs a belt —14— designed to transmit the power from said wheel to the dental-instrument (not shown).

To one end of the shaft —10— is secured a collar 90 —15— and between said collar and adjacent bracket-arm —8— and surrounding the shaft is a spiral-spring —16— serving to move the said shaft in one direction to maintain the wheel —11— normally over the depression —7— in the disk —6— and thus out of contact 95 with said disk as shown in Figs. 1 and 4 of the drawings. This movement of the shaft is limited by means of a stop-collar —17— fastened to the shaft and adapted to engage the other bracket-arm —8X— as shown in Figs. 1 and 5.

To the end of the shaft, adjacent to the stop-collar, is pivotally connected one end of a rod —18— which has its opposite end pivotally connected to the upper end of an upright arm —19— which is rigidly secured at its lower end to a rock-shaft —20— disposed below the 105 shaft —10— and at right angles thereto. Said rock-shaft is journaled in a sleeve —21— formed on the bracket-arm —8X—. Adjacent to the sleeve —21—, the bracket-arm —8X— is formed with a depending-arm —22— and on this arm is supported a segmental electric-contact plate —23— arranged concentric with the axis of the rock-shaft 20—. Said contact-plate is prefer- 110

ably fastened to the front side of the arm —22— by means of a screw —24— which passes through the arm and has one end entering the plate and the opposite end entering a binding-post —25— disposed at the rear side 5 of the arm, to which binding-post is connected the wire —2— of the electric-circuit.

The contact-plate —23— is insulated from its support as indicated at —26—, and the attaching-screw —24— passes through an aperture —27— in the arm 10 which is of sufficient size to prevent an electric-contact between the arm and screw, which latter forms part of the electric-circuit as clearly shown in Fig. 6 of the drawings. The said contact-plate is provided with a block of insulating material —28— which is preferably 15 set in the plate substantially at the center of its length as shown in Fig. 7.

—29— denotes a circuit-making and breaking switch which consists of a depending bar secured at its upper end to the aforesaid rock-shaft —20— and is provided 20 at its lower end with an electric-contact —30— adapted to move over the contact-plate —23—. The contact —30— consists preferably of a pin fastened to a binding-post —31— carried on the switch and insulated therefrom as indicated at —32—. To said binding-post is 25 connected the wire —2— of the electric-circuit as clearly shown in Fig. 6.

It is obvious that the conducting-wire —2— is cut to permit the same to be attached to the two binding-posts —25— and —31—.

30 To the rock-shaft —20— is also secured a grooved wheel —33— operative for turning the shaft in one direction for the purpose hereinafter explained.

—34— denotes a disk which is provided with circumferential groove —34X— and is pivotally connected 35 to an annular plate —35— fastened by means of screws —36— to the floor of the room or apartment in which the dental-instrument is to be used. The disk —34— is connected to the wheel —33— by means of a belt —37— which is connected to the disk as indicated at 40 —35X— and runs on a pair of pulleys —38—38— mounted on a plate —39— designed to be fastened to a wall or other support disposed substantially in a plane with the wheel —33— and also running on a pair of pulleys —40—40— mounted on brackets —41—41— secured 45 to the wall near the floor as clearly shown in Figs. 1, 2 and 3 of the drawings. The said disk —34— is formed with radially extending arms —42—42— serving as levers to permit the same to be operated by the foot of the person using the dental-instrument, for the purpose 50 of controlling the power-transmitting mechanism and circuit-making and breaking switch. I prefer to pivotally connect the disk —34— to the floor-plate —35— by providing the latter with a central post —43— which passes through a hub —44— formed on the disk. The 55 said post is provided in its upper end with a threaded socket for the reception of a screw —44X— and the post projects above the hub of the plate so as to leave a small space between the screw-head and hub, whereby the disk —34— is allowed a slight vertical play.

60 The lower face of the disk —34— is provided with a pair of radially disposed lugs —45—45— which are adapted to normally engage correspondingly arranged recesses —45X—45X— provided in the upper face of the plate —35—. The lugs and recesses are rounded 65 transversely so as to permit their disengagement when

the operator's foot is pressed against one of the arms —42— on the disk —34— to rotate the latter. To limit this rotary motion of the disk, I provide the latter with a lug —46— adapted to engage lugs —47—47— on the plate —35— as illustrated in Figs. 9 and 10 of the drawings. 70

The operation of the described dental-engine and controlling means will now be described. The power-transmission-wheel —11— is held normally over the central depression —7— of the friction-disk —6— by 75 the expansive force of the spiral-spring —16— on the shiftable shaft —10—, and thus the wheel is out of contact with the disk, and at the same time the electric-switch —29— is held in position to cause its contact —30— to bear on the insulating block —28— in 80 the contact-plate, to open the electric-circuit to cut out the motor. When the parts are in normal position, it will be understood that the foot-operated disk —34— is disposed with its lugs —45—45— in engagement with the recesses —45X—45X— in the plate —35—. This 85 engagement serves to prevent accidental turning of the disk. When it is desired to use the dental-instrument, the operator applies the foot to one of the arms —42— on the disk —34— for the purpose of turning the disk, whereby the belt —37— and wheel —33— are caused 90 to turn the rock-shaft —20— to the left as viewed in Fig. 1 of the drawings. By this movement of the rock-shaft, the arm —19— and rod —18— are actuated to shift the shaft —10— to the left in opposition to the spiral-spring, whereby the wheel —11— is carried correspondingly and caused to frictionally engage the disk —6— secured to the motor-shaft. Simultaneously with the movement of the wheel —11— into engagement with the disk —6—, the electric-switch —29— is actuated by the said rock-shaft —20— so as to cause 95 the electric-contact —30— to bear on the contact-plate —23— and thereby close the circuit. This closing of the electric-circuit obviously starts the motor —1— and thus the disk —6— is caused to drive the wheel —11— and belt —14— which is designed to transmit 100 the power to the dental-instrument, (not shown), it being understood that the person using the instrument retains the foot against the arm —42— of the disk —34—. If it is desired to increase the speed of the dental-instrument, the operator turns the floor-disk —34— to a greater degree whereby the shaft —10— is shifted to carry the wheel —11— a further distance from the center of the friction-disk —6— so as to drive the wheel —11— faster, and thus the wheel and belt —14— are caused to transmit correspondingly increased 110 speed to the instrument. By releasing the arm —42— of the disk —34— from pressure of the foot to a degree, the spiral-spring —16— is allowed to exert expansive force on the shaft —10— whereby the latter is caused to be shifted in reverse direction and thus the wheel —11— is carried toward the center of the disk —6— to decrease the speed. 115

It will be apparent that the person using the dental-instrument very easily and conveniently controls the transmission-mechanism so as to regulate the speed of 120 the instrument.

When the arm —42— on the floor-disk —34— is released from the operator's foot, the action of the spring —16— moves the wheel —11— out of operative relation with the disk —6—, i. e. to cause the wheel to stand 130

over the central depression —7— in the disk —6— as shown in Figs. 1 and 4 of the drawings. This reverse movement of the shaft —10— causes the rod —18— and arm —19— to correspondingly turn the rock-shaft —20—, whereby the electric-switch —29— is actuated to cause its contact —30— to bear on the insulating block —28— secured to the plate —23—. This bearing of the contact —30— on the block breaks the electric-circuit and thus cuts out the motor simultaneously with the throwing of the transmission-wheel —11— out of operative relation with the disk —6— on the motor-shaft.

To adjust the motor-shaft —5— vertically to regulate the pressure of the friction-disk —6— on the transmission-wheel —11—, I employ a horizontally-disposed plate —48— secured by means of screws —49— to the end of a hub —50— on the bottom of the motor-case, which plate is provided with a screw-threaded aperture —51— disposed axially in line with the shaft —5— and receives a screw —52— bearing against the lower end of the said shaft. By turning this screw —52— to the right, the shaft is lifted to carry the disk —6— toward the wheel —11—, and by turning the screw to the left, the shaft is allowed to drop by gravity whereby the pressure of the disk on the wheel is decreased.

The screw —52— is provided with a set-nut —53— for securely retaining the shaft in its adjusted position as clearly illustrated in Fig. 4 of the drawings.

30 What I claim as my invention is:—

1. In combination with an electric-motor and circuit therefor, a power-transmitting mechanism adapted to be thrown into and out of operative relation with the motor, and circuit-making and breaking means controlled by the said power-transmitting mechanism as and for the purpose set forth.

40 2. In combination with an electric-motor and circuit therefor, a power-transmitting mechanism adapted to be thrown into and out of operative relation with the motor, a normally open switch in the electric-circuit, means controlled by the power-transmitting mechanism for moving said switch to its closed position, and means for automatically moving the switch to its normal position as and for the purpose set forth.

45 3. In combination with an electric-motor and circuit therefor, a variable-speed power-transmitting mechanism adapted to be thrown into and out of operative relation with the motor, and circuit-making and breaking means controlled by the power-transmitting mechanism as and for the purpose set forth.

50 4. In combination with an electric-motor and circuit therefor, a power-transmitting mechanism adapted to be thrown into and out of operative relation with the motor, a normally open switch connected to the electric-circuit, means controlled by the power-transmitting mechanism for closing the said switch when the mechanism is in its operative condition, and a spring adapted to actuate the switch-operating means to open the switch when the aforesaid mechanism is thrown out of operative relation with the motor as set forth.

55 5. In combination with an electric-motor and circuit therefor, a variable-speed power-transmitting mechanism normally out of operative relation with the motor, a normally open switch in the electric-circuit, manually-operated means for throwing the power-transmitting mechanism into operative relation with the motor, means controlled by the power-transmitting mechanism for closing the switch when the said mechanism is thrown into its operative condition, and a spring adapted to simultaneously throw said mechanism out of operative relation with the motor and move the switch to its normal position as set forth.

60 6. In a dental-engine, the combination of an electric-

motor having a suitable supply circuit, a power-transmitting mechanism comprising an irrevoluble longitudinally-shiftable shaft and a wheel journaled on said shaft and adapted to be moved thereby into and out of operative relation with the motor, manually operated means for shifting the shaft in one direction, means automatically shifting said shaft in opposite direction, a normally open circuit-maker and breaker in the electric-circuit, and means actuated by the aforesaid shaft for operating said circuit-maker and breaker as and for the purpose set forth.

75 7. In a dental-engine, the combination with an electric-motor having a suitable supply circuit and an inclosing-case, of a power-transmitting mechanism mounted on the motor-case, a circuit-making and breaking device supported on said motor-case, and means controlled by the power-transmitting mechanism for operating the circuit-making and breaking device as and for the purpose set forth.

80 8. In a dental-engine, the combination with an electric-motor having a supply circuit and an inclosing-case, of a power-transmitting mechanism mounted on the motor-case, a manually operated device connected to the transmission-mechanism for varying the speed thereof, and for throwing the same into operative relation with the motor, a normally open circuit-making and breaking switch connected to the circuit, means controlled by the manually operated device for moving said switch to its closed position, and automatic means for throwing the transmission-mechanism out of operative relation with the motor and simultaneously moving the switch to its normal position as set forth.

85 9. In a dental-engine, the combination with an electric-motor having a supply-circuit and an inclosing-case, of a power-transmitting mechanism mounted on the motor-case and comprising an irrevoluble longitudinally-shiftable shaft and a wheel journaled on said shaft and driven by the motor, said wheel being normally out of operative relation with the motor, manually operated means for shifting the shaft in one direction to move the wheel into operative position, a spring adapted to shift said shaft in opposite direction to move the wheel to its normal position, a normally open switch connected to the electric-circuit, and means connecting the aforesaid shaft to the switch and operative for moving the switch to circuit-making and breaking position simultaneously with the movement of the transmission-wheel into and out of operative relation with the motor as set forth.

90 10. In a dental-engine, the combination with an electric-motor and circuit therefor, of a power-transmitting mechanism comprising a wheel adapted to be shifted into and out of operative relation with the motor-shaft, shifting-mechanism including a rock-shaft, and a circuit-maker and breaker actuated by said rock-shaft as set forth.

95 11. In a dental-engine, the combination with an electric-motor and circuit therefor, of a power-transmitting mechanism comprising a wheel adapted to be shifted into and out of operative relation with the motor-shaft, shifting-mechanism comprising a rock-shaft, manually operated means for turning the rock-shaft, in one direction and automatically operating means for turning said shaft in reverse direction, and a normally open circuit-making and breaking switch actuated by said rock-shaft as and for the purpose set forth.

100 12. In a dental-engine, the combination with an electric-motor and circuit therefor, of a variable-speed power-transmitting mechanism, means for throwing said mechanism into operative relation with the motor, and comprising a rock-shaft connected to said mechanism, and circuit-making and breaking means controlled by said rock-shaft as set forth.

105 13. In a dental-engine the combination with an electric motor and circuit therefor, of a variable-speed power-transmitting mechanism comprising a wheel adapted to be shifted into and out of operative relation with the motor-shaft, mechanism for shifting said wheel into operative position comprising a rock-shaft having suitable connections with the aforesaid wheel, and manually operated means for turning the rock-shaft in one direction, a spring adapted to shift the aforesaid wheel out of operative position and to turn the rock-shaft in reverse direction, a stationary electric-contact and a movable-contact in the circuit, said movable-contact being actuated by the rock-

- shaft and moved into and out of engagement with the stationary contact simultaneously with the shifting of the aforesaid transmission into and out of operative relation with the motor as and for the purpose set forth.
- 5 14. In a dental-engine, the combination with an electric-motor and circuit therefor, of a variable-speed power-transmitting mechanism comprising an irrevolute longitudinally-shiftable shaft and a wheel journaled on said shaft and adapted to be moved thereby into operative relation with the motor-shaft, manually operated means including a rock-shaft for shifting the aforesaid shaft in one direction, and automatic means for shifting the same in opposite direction, a lever connecting the rock-shaft with the shiftable shaft, and a circuit-making and breaking switch fastened to said rock-shaft as and for the purpose set forth. 85
- 10 15. In a dental-engine, the combination with an electric-motor, of a power-transmitting mechanism, comprising a wheel and a belt driven thereby, manually operated means including a rock-shaft and lever for moving said wheel into operative relation with the motor, spring-actuated means for automatically moving said wheel out of operative position, a stationary contact-plate connected to the electric-circuit, and a circuit-making and breaking member fastened to the aforesaid rock-shaft and movable over said contact-plate as set forth. 90
- 15 16. In a dental-engine, the combination with an electric-motor and circuit therefor, of a variable-speed power-transmitting mechanism, a foot-operated device for controlling said mechanism, and a circuit-maker and breaker connected to the foot-operated device as and for the purpose set forth. 95
- 20 17. In a dental-engine, the combination with an electric-motor and circuit therefor, of a variable-speed power-transmitting mechanism, foot-operated devices including a rock-shaft for throwing said mechanism into operative relation with the motor, and spring-actuated means for automatically throwing the mechanism out of operative relation with said motor, an electric-contact connected to the circuit, and a switch in the circuit and fastened to the aforesaid rock-shaft, said switch being movable into engagement with the contact-plate by the action of the foot-operated devices and moved out of engagement with said contact-plate by the spring-actuated means as set forth. 100
- 25 18. In a dental-engine, the combination with an electric-motor and circuit therefor, of a power-transmitting mechanism comprising a shiftable wheel normally in inoperative position in relation to said motor, a rock-shaft connected to the said wheel, a pulley secured to said rock-shaft, a foot-operated device, a belt connecting said foot operated device and pulley and adapted to turn the rock-shaft in one direction to shift the aforesaid transmission-wheel into operative position, a spring operative for shifting the said wheel out of operative position, and a circuit-maker and breaker secured to the rock-shaft and moved thereby to circuit-making position through the action of the foot-operated device and moved to circuit-breaking position through the action of the aforesaid spring as set forth and shown. 105
- 30 19. In a dental-engine, the combination with an electric-motor and its supply circuit and motor inclosing-case, of a mechanism comprising an irrevolute longitudinally-shiftable shaft supported on the motor-case, a wheel journaled on said shaft, and a power-transmitting belt driven by said wheel, a spiral-spring surrounding said shaft and operative for holding the wheel normally out of operative relation with the motor-shaft, a rock-shaft supported on the motor-case, a lever rigidly connected at one end to the rock-shaft, a rod pivotally connected to the free end of said lever and to the aforesaid shiftable shaft, a grooved wheel fastened to the said rock-shaft, a grooved wheel having a suitable floor-attachment, a belt connecting said grooved-wheels, foot-actuated means connected to the wheel on the floor and operative for turning the rock-shaft in one direction to shift the transmission-wheel into operative relation with the motor-shaft, and a circuit-maker and breaker controlled by said rock-shaft as and for the purpose set forth. 110
- 35 20. In a dental-engine, the combination with an electric-motor having an inclosing-case and a supply-circuit, of a bracket supported rigidly upon the motor-case, an irrevolute horizontal shaft mounted longitudinally shiftable on said bracket, a wheel journaled on said shaft and adapted to be driven by the motor, manually-operated means for shifting the shaft in one direction to move the wheel into operative relation with the motor, a spring for automatically shifting said shaft in reverse direction to move the wheel out of operative position, a normally closed switch connected to the electric-circuit and supported on the aforesaid bracket, and means actuated by the shiftable shaft for moving the switch to circuit-making and breaking positions as set forth. 115
- 40 21. In a dental-engine, the combination with an electric-motor having an inclosing-case, and a supply-circuit, of a bracket mounted upon the motor-case, and irrevolute shaft supported longitudinally-shiftable on said bracket and provided at one end with a collar, a wheel journaled on said shaft and moved thereby into and out of operative relation with the motor, a rock-shaft journaled on the bracket and connected to the aforesaid shaft and adapted to shift the same in one direction to move the wheel into operative position, manually-operated means for actuating the rock-shaft, a spiral-spring surrounding the said shiftable shaft, and interposed between the collar thereon and the bracket, and serving to force the shaft in opposite direction to move the wheel out of operative position, a switch connected to the electric-circuit and actuated by the rock-shaft, said switch being held normally in circuit-breaking position by the action of said spring, and moved to circuit-making position by the manually-operated means as set forth. 120
- 45 22. In a dental-engine, the combination with an electric-motor and circuit therefor, of a frictionally-driven power-transmitting mechanism, manually operated means for throwing said mechanism into operative relation with the motor, means for automatically throwing said mechanism out of operative relation with the motor, a normally open circuit-making and breaking switch connected to the electric-circuit and moved to circuit-closing position by the manually-operated means, and means controlled by the power-transmitting mechanism for automatically moving the switch to its normal position simultaneously with the throwing of said mechanism out of operative relation with the motor as set forth. 125
- 50 23. A dental-engine comprising an electric-motor provided with an inclosing-case and having a suitable supply-circuit, a disk fastened to the motor-shaft, a shiftable power-transmission wheel supported on the motor-case and adapted to be driven by frictional engagement with said disk, means for moving said wheel into and out of contact with the disk, and circuit-making and breaking means arranged and operating in the manner set forth. 130
- 55 24. A dental-engine comprising an electric-motor having a suitable supply-circuit and provided with an inclosing-case, a variable-speed friction power-transmitting mechanism supported on the motor-case, manually-operated means for controlling said mechanism, and an electric-circuit-maker and breaker controlled by said manually operated means as set forth. 135
- 60 25. A dental-engine comprising an electric-motor having a supply-circuit, a disk secured to the shaft of the motor, an irrevolute longitudinally-shiftable shaft supported above the motor, a power-transmission wheel journaled on the latter shaft and shifted thereby and adapted to frictionally engage the aforesaid disk, said wheel being adapted to be moved radially in relation to the disk to vary the speed of the wheel and to be carried into and out of contact with the said disk, manually-operated means for shifting the said shaft in one direction, automatic means for shifting the shaft in reverse direction, an electric-switch connected to the circuit, mechanism actuated by the manually-operated means for moving the switch to circuit-making position, and actuated by the automatic means to move the same to circuit-breaking position as set forth. 140
- 65 26. In a dental-engine, the combination of an electric-motor provided with an inclosing-case and having its shaft disposed vertically, a disk secured to the upper end of the motor-shaft, a bracket supported upon the motor-case, a 145
- 70
- 75
- 80

horizontally disposed shaft mounted on the bracket and extending diametrically over the aforesaid disk, a power-transmission wheel mounted on the horizontal shaft and frictionally-driven by the aforesaid disk, said wheel being 5 adapted to be shifted radially in relation to the disk to vary the speed of the wheel, means for shifting the said wheel, and means for adjusting the disk in relation to the transmission-wheel as set forth.

27. In a dental-engine, the combination of an electric-10 motor having the longitudinally-adjustable shaft, a friction-disk fastened to said shaft, an irrevolvable longitudinally-shiftable shaft disposed at right angles to the motor-shaft, and extending diametrically across the friction-disk, 15 a power-transmission wheel journalized on the shiftable shaft and held against longitudinal movement thereon, said wheel being driven by frictional engagement with the disk, manually controlled means for shifting the latter shaft to move the wheel radially on the disk to vary the speed of the wheel, and means for adjusting the motor-20 shaft to regulate the pressure of the disk on the transmission-wheel as set forth.

28. In a dental-engine, the combination of an electric- 20 motor having a suitable supply-circuit and provided with an inclosing-case, the motor-shaft being disposed vertically

and having its upper end protruding from the case, a friction-disk secured to said end of the shaft, a bracket supported on top of the case and comprising a pair of upwardly extending arms provided with bearings disposed in horizontal alinement, an irrevolvable shaft mounted longitudinally shiftable in said bearings, a power-transmission 25 wheel journalized on the latter shaft and adapted to be driven by the said friction-disk, said wheel being normally out of contact with the disk and moved by the shaft radially across the disk to vary the speed of the wheel, a rock-shaft supported on the aforesaid bracket, an arm and 30 a grooved-wheel rigidly fastened to the rock-shaft, a rod connecting said arm to the shiftable shaft, a foot-operated annular plate having a suitable pivotal connection with floor, a belt connecting said grooved-wheel and grooved-plate and operative for moving the shiftable shaft in one 35 direction, and a spring for automatically moving said shaft in reverse direction, a switch connected to the electric-circuit and fastened to the aforesaid rock-shaft as and for the purpose set forth.
